UNITED STATES PATENT OFFICE

2,077,203

DAM

Theodor Becher, Wiesbaden, Germany, assignor to Maschinenfabrik Augsburg-Nürnberg, A. G., Nuremberg, Germany, a corporation of Germany

Original application September 18, 1935, Serial No. 41,079. Divided and this application December 3, 1936, Serial No. 113,997. In Germany September 27, 1934

1 Claim. (Cl. 61—25)

This invention relates to dams of the type adapted to extend across a stream or river to dam up the water flowing therein, and more particularly to dam structures of the type having a stationary section and a movable section coextensive with the stationary section, and is a division of my prior application filed in the United States Patent Office September 18, 1935, Serial No. 41,079.

Heretofore it has been proposed to construct dams with a movable member such as a flap, wicket or the like, so as to increase the depth of the water in the pool on the upstream side of the dam.

When a movable flap is employed, the flap is hingedly connected along one edge to the top of the stationary dam structure, and this flap is adapted to be swung about the pivot provided by the hinge from a substantially horizontal to a substantially vertical position. The flap permits the passage of a smaller or larger amount of water according to the relative position thereof.

In actual practice it is not difficult to mount a flap upon a stationary weir or upon a dam wall, the top or crest of which is at a considerable distance above the bed of the river. However, if the dam wall is merely a sill and the hinge of the flap is located near the bed of the river, it is necessary to provide a cavity or recess in the dam for receiving the flap, so that when the flap is disposed in a horizontal or inoperative position, it will not hinder navigation, discharge of high water, and the like.

When a cavity is formed in the stationary dam structure, sand, shingle, mud, and other foreign matter, collects in the cavity, and causes considerable trouble, due to the fact that the flap cannot be moved into the cavity on account of the presence of foreign matter therein.

An object of the present invention is to provide means for scavenging or removing foreign matter, such as sand, shingle, mud and the like from a cavity of a dam of the type having a flap pivotally mounted thereon and adapted to be disposed in the cavity.

Other objects and advantages of the invention will be apparent during the course of the following description.

In the accompanying drawings:—

Figure 1 is a transverse section of a dam constructed according to the present invention; and

Fig. 2 is a plan of the structure shown in Fig. 1.

Referring to the drawings, the main dam structure 11 comprises a masonry body formed on the bed of a stream or river and extending across

the river from shore to shore. The masonry employed for constructing the dam 11 may be of any suitable material, such as concrete or the like.

At each end the dam 11 is formed with an upstanding end wall 12, only one of which is shown in the drawings. The end walls 12 may extend upwardly any desired height and be of any desired length up and down the stream with respect to the dam.

As shown in Fig. 1, the main body of the dam 11 has a front or upstream wall 13, a bottom 14, and a top 15. The bottom 14 is longer than the top, for a purpose to be hereinafter described.

Mounted upon the top 15 at a point adjacent the rear end thereof is a flap 16, which is pivotally connected along its lower longitudinal edge to the dam by hinges 17.

As shown, the flap may consist of two curved plates 18, 19 which are firmly united with one another at their upper and their lower edges.

The radius of curvature of the plate 18 is longer than the radius of curvature of the plate 19, and the circumferential lengths of the plates are such that they enclose between them a space, having in transverse section, the shape of a fish's belly, or resembling a mathematical biangle, respectively.

The flap 16 is actuated in known manner from one of its ends. I have abstained from showing the driving means because they are known and do not, therefore, form a part of this invention. To actuate the flap 16 from one of its ends, is admissible also in the present case, since the flap, designed and shaped as shown and described, is a bending-proof and torsion-proof structure.

In order to permit the flap 16 to be swung downwardly to a position in which the flap will not hinder navigation, discharge of high water, and the like, a cavity 21 is formed in the portion of the dam 11 on the downstream side of the flap.

As shown in Fig. 1, the cavity 21 has a front, substantially vertical wall 22, which is disposed a slight distance downstream from the point at which the hinges 17 are connected to the top 15 of the dam. The bottom of the cavity 21 curves upwardly slightly downstream from its junction with the bottom of the vertical wall 22, so that the cavity provides a recess having a suitable contour for the flap 16 when the flap is disposed in the cavity, as shown by dotted lines, Fig. 1.

Due to the fact that sand, shingle and other foreign matter collects in the cavity 21, it is desirable to provide means whereby such foreign matter can be flushed or removed from the cav-

ity, so that the flap 16 can be disposed therein when desired.

According to the present invention the scavenging means comprises a channel or passage 23 which is formed in the dam 11 beneath the top 15 and in spaced relation in front of the front wall 22 of the cavity 21. This channel 23 extends across the entire length of the dam 11 from one end 12 thereof to the other and is entirely enclosed.

The channel 23 is separated from the cavity 21 by the wall 22, which wall may be of any suitable thickness, and the bottom of the channel 23 lies in substantially the same plane as the bottom 15 of the cavity 21 adjacent the wall 22.

The channel 23 is in communication with the cavity 21, so that water in the channel 23 can flow into the cavity 21, through a series of slots 24 formed in the bottom of the wall 22.

As shown in Fig. 2, the slots 24 are separated by relatively narrow vertical walls or columns 25. It is necessary to provide the columns 25 so as to anchor the lower portion of the wall 22 to the bottom of the dam, but said walls or columns are so formed as to not interfere to any great extent with the flow of water from the channel 23 into the cavity 21.

At a suitable point upstream with respect to the dam 11, one of its end walls 12 is formed with an opening 27 which is connected to the channel 23 by a passage 28.

In order to prevent the passage of sticks and other foreign matter through the passage 28, a suitable screen 29 is mounted on the end wall 12 in front of the opening 27 (see Fig. 2).

The passage 28 constitutes a by-pass through which water can be conducted from the pool on the upstream side of the dam to the channel 23 and from thence to the cavity 21, for the purpose of flushing the cavity, and in order to control communication through the passage 28, a gate or shutting-off member 30 is provided. The gate 30 may be mounted at any suitable point in the passage 28, and said gate may be of any approved type by which the amount of water flowing through the by-pass provided by the

passage 28 can be regulated, so as to permit various amounts of water to flow into the channel 23, or the flow of water to said channel completely cut off.

The water flowing from the head water 5 through the by-pass 28 is subjected to the pressure exerted by the head water, and therefore the water rushing from the channel 23 through the slots 24 into the cavity 21 drives the shingle, sand, and other foreign matter out of the cavity. 10

Preferably the slots 24 should be so formed as to have a sectional area of such a size that the amount of water flowing through said slots is less than the amount being added to the head water so that the water flowing through the slots 24 is always subjected to the full pressure of the head water, and the scavenging is, therefore, effected energetically under that pressure. 15

Having thus described my invention, what I claim is:—

A dam comprising a main body disposed on the bed of a stream and having an upper portion and a lower portion, with a vertical wall connecting both portions, the lower portion constituting a cavity extending across the stream the entire length of the dam, an end wall projecting upwardly from each end of the dam, a movable flap hingedly connected along one edge to the upper portion of the dam adjacent said vertical wall, said flap being adapted to be disposed in said cavity when swung downwardly from an upright position, an enclosed channel formed in the dam on the upstream side of said vertical wall, said channel being coextensive with the cavity and being spaced therefrom by said vertical wall, a series of slots formed in the dam between the bottom of said channel and the bottom of said cavity through which water can flow from the channel into said cavity, said slots extending throughout the entire length of the channel, a by-pass formed in one end of the dam and connecting the channel with the head water above the dam, and means for controlling the amount of water flowing through said by-pass. 35 40 45
